SUBMARINE CABLE

Application filed February 12, 1931, Serial No. 515,256, and in Spain April 29, 1930.

This invention relates to submarine cable telephone transmission systems. In such systems wherein it is required to transmit telephone signals between two stations separated by long distances, it is necessary to have means at the terminals of the cable for directing to the proper amplifiers the telephone signals according to their direction of transmission.

It has heretofore been proposed to accomplish this by using a balanced transformer for coupling the transmitting and receiving branches to the cable terminal. This arrangement had many disadvantages mainly due to the impossibility of obtaining or maintaining accurate balance, which gives rise to interference between the two branches.

The present invention provides an improved system and broadly comprises a submarine telephone cable transmission system comprising terminal amplifiers and means controlled by voice frequency currents for operating the switching of the terminal amplifiers according to the direction of transmission, delay networks for preventing undue loss of signals during the switching operations in combination with means which in known manner momentarily protect the receiving apparatus from discharge currents immediately after the terminal connections are switched from the transmitting condition to the receiving condition.

Furthermore the invention as above may be represented in different practical embodiments or alternatives which will be described hereinafter so that the full scope of the invention may be readily understood.

Other features also contributing to the practical success of the invention will also be evident from a perusal of the following description and will be pointed out more clearly in the appended claims.

It may sometimes be desirable that the cable system provides telegraph facilities as well as telephony and the following description will reveal how the telephone system according to the invention may be a modification be used in a system over which both telephone and telegraph communications may take place. The direction of telegraph trans-

mission may be either dependent or independent of the direction of speech.

In the accompanying drawings Fig. 1 illustrates the invention as applied to the terminal equipment for a system adapted solely for 55 telephony.

Fig. 1A illustrates a suitable means for connecting the equipment of Fig. 1 to a land line.

Fig. 1B illustrates an arrangement whereby the switching controlled according to the co arrangements of Fig. 1 may be extended over a repeater situated at an intermediate point in the cable circuit.

Fig. 1C illustrates a modification of Fig. 1B.

Fig. 1D illustrates an arrangement which when connected to either points A and A₁ or B and B₁ of Fig. 1C will terminate the cables CW and CE respectively so that the equipment of Fig. 1C may serve either as a repeater 70 over the extreme ends of the cable or as a terminal for either cable which is connected to it.

Fig. 2 is a schematic diagram illustrating a cable provided with telegraph facilities as 75 well as telephony.

Fig. 3 shows a modified arrangement according to the invention also for telephone and telegraph and in which courier currents are used for switching.

Fig. 3A illustrates a repeater arrangement using courier current control.

Fig. 4 and Fig. 4A illustrate terminal equipment of a submarine cable telephone and telegraph system.

With reference to Fig. 1 the arrangement will be best understood by reference to the functioning of its parts. Suppose that telephone signals arrive on line L₁ on the top left hand of the figure, they are passed through amplifier A₅ and reach a branching point. The main signals pass to a delay network D₂ where the transmission of the message in this direction is delayed for a predetermined period. Meantime the currents traversing the other branch path traverses an amplifier detector (preferably made sensitive only to that part of the frequency range which lies below about 1,200 cycles per second) AD₃ in whose output circuit is a wind- 100

ing for operating relay S_3 . This relay on operation closes a circuit for relay S_5 and removes a short circuit from the relay of switch LS_1 . The function of the relay S_5 will be explained later.

Switch LS_1 closes its inner contacts and thereby connects the line L_1 to a transformer T_1 . When this has taken place the speech signals have traversed the delay network D_2 ,

an equalizer E_1 which is adapted partially to equalize the attenuation of the signal frequencies to be transmitted over the cable, and the amplifier A_7 to the switch contacts LS_1 . AVC_1 is an automatic volume control device for controlling the output from the amplifier A_5 . $V1_3$ is a volume indicator for measuring the actual level of the speech being delivered to the submarine cable. VL_1 is a voltage limiter which will be explained later.

During the transmission of speech from line L_1 to the transformer T_1 (which may be iron or air cored) the circuit of line L_2 is short circuited by the switch S_5 . When the speech input from the line L_1 ceases, relay S_3 releases. S_5 , however does not release until later than LS_1 after the cessation of speech, thus ensuring that any noise occurring at the moment of connection of the receiving branch L_2 to the transformer T_1 will

not be transmitted through the line L_2 . When the speech is received over cable C it passes through transformers T_2 and T_1 over the switch LS_1 , outer contacts to an amplifier A_{10} . It then traverses an equalizer E_2 which is designed to complete the equalization of the signals transmitted in this direction which were partly equalized at the transmitting end. The signal then traverses an amplifier A_8 , amplifier A_6 to the line L_2 .

$V1_1$ is a volume indicator similar to $V1_3$. Between the amplifiers A_8 and A_6 a branch path is taken through an amplifier detector AD_4 for operating the switch S_4 which when energized short circuits the amplifier A_5 and amplifier-detector AD_2 connected to the line L_1 . The release of the relay S_4 is delayed for the cessation of speech by a time equal to twice the transmission time of the four-wire circuit L_1 , L_2 ; this prevents the false operation of amplifier detector AD_3 and the relays S_2 , S_5 and S_1 by echo currents from the termination of the circuit.

In the above description we have referred to speech signals arriving on line L_1 and being received in the line L_2 . In Fig. 1A there is shown an arrangement for connecting the lines L_1 and L_2 to a land line such as TB_1 . Signals arrive in line TB_1 from a subscriber's station; they pass through the balanced transformer HC_1 of ordinary construction employing a balancing network N . They then pass through amplifier A_1 in whose input circuit is a gain control device GC_1 which is either under the control of the voice currents or may be manually controlled. In

the output of A_1 is a branch circuit leading through a delay network D_1 through an amplifier A_3 and to the line L_1 . The other branch is through an amplifier detector AD_1 which controls the switch S_1 which short-circuits an amplifier in the line L_2 . Transmission in the path L_2 from the amplifier A_6 of Fig. 1 takes place over amplifier A_4 , gain control device GC_2 , amplifier A_2 to the transformer HC_1 . The output of the amplifier A_4 is shunted by an amplifier detector AD_2 for operating a switch S_2 which shortcircuits amplifier A_1 in the transmitting branch. The relay S_2 is shown having the second winding connected through a rheostat VHO . The object is to vary the release time of the relay S_2 , after the cessation of the speech from the line L_2 . This is delayed so that the relay S_2 will not be released until all echoes received from extensions connected to TB_1 have been received and suppressed by the contacts shortcircuiting the input to the amplifier detector AD_1 .

In Fig. 1B a telephone repeater equipment is illustrated such as may be situated in an island lying intermediately in the cable route. The equipment uses branches for conducting the signal from either direction through a power amplifier A_{12} . The repeater is normally conditioned for through transmission in neither direction but is so adapted that on receiving signals from one direction a through circuit is established whilst the branch adapted to receive in the opposite direction is disabled.

A signal arriving from cable CW to the transformer T_3 , T_4 passes over the outer contacts of switch LS_2 over amplifier A_9 , equalizer E_3 , amplifiers A_{11} and A_{13} to a delay network D_3 . Across the output of the amplifier A_{11} is shunted an amplifier detector AD_5 for operating a relay S_8 . This relay in turn operates relay S_9 which on closing its contacts shortcircuits an amplifier A_{16} in the branch adapted for transmitting in the opposite direction and this branch is therefore disabled. The switch S_8 in operating also removes the shortcircuit from the switch LS_3 which closes its inner contacts. These switching operations are adapted to take place during the delay in the signals by the network D_3 . From this network the signals pass through the power amplifier A_{12} and to the inner contacts of switch LS_3 and thence through transformers T_5 and T_6 to the cable CE . VL in the output of the amplifier A_{12} is an equipment for adjusting signal levels. Signals received in the opposite direction, i. e. from cable CE pass through the outer contacts of switch LS_2 through amplifier A_{18} equalizers E_4 , amplifiers A_{16} and A_{14} to the delay network D_3 , power amplifier A_{12} and to the inner contacts of switch LS_2 to the line, the contacts of switch LS_2 being closed by means of switch S_6 over the amplifier de-

tector AD_6 which operates similarly to the equipment already described for the opposite direction of transmission. Similarly S_7 shortcircuits the amplifier A_{11} . The shortcircuit placed on amplifiers A_{16} or A_{11} respectively by the relays S_9 and S_7 protects the amplifier A_{12} from noise from the unused branch during the transmission of speech.

In Fig. 1C is illustrated a modification of a repeater equipment which might substitute that of Fig. 3. This equipment, however, provides the additional facility that it may be used either as a repeater from the cable CW to the cable CE or it may be used as a terminal equipment for both the cable CW and the cable CE. We shall describe later the additional apparatus which may be adapted to the equipment of Fig. 1C to enable this additional facility to be used. The equipment of Fig. 1C is practically identical with that of Fig. 1B with the exception that no common power amplifier is used, but instead two separate amplifiers A_{19} and A_{20} are provided. The switching conditions and the shortcircuiting relays are indicated by similar reference letters as in Fig. 1B and since the operation is substantially the same it is thought that its operation will be evident without detailed description.

In Fig. 1D an equipment is shown which may be connected to the circuit of Fig. 1C so that the terminals A_3 correspond with the terminals A or B and the terminals B_3 correspond respectively to the terminals A_1 or B_1 . In the first case it would act as a terminal equipment to the cable CW and in the second case it would act as a terminal equipment to the cable CE. Assuming the contacts of A_3 correspond to B and B_3 to B_1 , the amplifier A_{22} would be connected to a delay network D_6 and the delay network D_5 to the amplifier A_{21} . Signals received from the cable CE would pass through amplifier A_{22} , through delay network D_6 , gain control device GC_4 , amplifier A_{26} to the hybrid coil HC_2 and the land line SB_2 . When transmitting in the opposite direction, signals from SB_2 pass over the transformer HC_2 through the gain control device GC_3 , amplifier A_{21} to the delay network D_5 of Fig. 1C. The function of the gain control devices and the delay networks with the switch gear of Fig. 1C is as before explained.

In the above arrangements there are no facilities provided for telegraph transmission, but this may be converted into a system for transmitting telegraphy as well as telephony by following the arrangements shown schematically in Fig. 2. In this figure the telephone branch from the cable C is over a filter TP which is adapted to pass telephone frequencies but to offer high attenuation to telegraph frequencies. Switch LS_1 corresponds to the switch of Fig. 1 bearing the same reference and the branches L_1 and L_2

also correspond with branches L_1 and L_2 of Fig. 1. The repeaters and other apparatus in these respective branches are indicated schematically by R_1 and R_2 . The two branches L_1 and L_2 terminate as before in the line TB_1 . The telegraph equipment for transmitting and receiving is connected to the cable C over the switch TS which when on its upper contact connects the telegraph receiving apparatus R through the amplifier R_3 to the cable C through a filter TG which is adapted to transmit telegraph currents and to exclude telephone currents. When the switch TS is on its lower contact the telegraph transmitter T is connected through the amplifier R_4 and filter T_g to the cable. The switch TS may be arranged to operate directly under the control of the switch LS_1 so that the movement of switch LS_1 causes a similar movement in the switch TS . A means for effecting this may be merely by connecting the two switch arms together as will be obvious. With such an arrangement the telegraph transmission will always be in the same direction as speech and known means would have to be provided for storing the telegraph messages during intervals of interruption due to the voice frequency switching. In a modification the switch TS may be quite independent of the switch LS_1 and may be governed in operation by the direction of telegraph transmission which is to take place over the cable, thus the first telegraph transmitter to function may be given control over the line by switching arrangements substantially the same as those employed for telephony in Fig. 1.

In Fig. 3 a system is shown in which the speech currents have not entire direct control of the switching.

In this system both speech and telegraph currents may be transmitted simultaneously, the direction of the telegraph current not being controlled in any way by the direction of the speech currents. The circuit is normally arranged for speech transmission in the direction opposite to that of telegraph transmission. One of the telegraph channels is reserved for the transmission of control currents to operate switchgear in the voice circuit, speech for transmission in the same direction as telegraph starts these control currents which operate the switchgear in the remaining part of the system unless the complete system is occupied by speech in the normally through direction. In this case a courier current is employed for controlling the switching of the telephone receiving and transmitting branches of the cable. In the figure the switches are in a position to connect the telegraph receiver to the cable. The terminal equipment of Fig. 3 is somewhat similar to that of Fig. 1 and similar parts in both figures bear the same reference letters. In the transmitting branch L_1 a filter

F_1 is provided for preventing telegraph frequencies from entering the cable and a similar filter F_2 is provided in the branch L_2 . With the switches in the position shown in Fig. 1 the branch L_1 is connected through the transformers T_1 , T_2 and a filter F_3 to the cable C . The terminal equipment at the other end of the cable C may be identical with that of Fig. 3 and at that station the switch corresponding to LS_1 would be in a position to connect the cable to the receiving branch corresponding with L_2 . If there is no transmission in the branch L_1 and a person at the other end of the cable begins to speak, a courier current is transmitted along the cable and received through the filter F_4 over the closed contacts of switch TS_{31} through equalizer TE , amplifier TA , receiver TR to a relay S_{38} which on closing its contact connects earth over the relay S_{31} . S_{31} on operating breaks the energizing circuit of relay S_{32} which on releasing ensures that earth is disconnected from the left hand side of the polarized relay S_{33} , so that the connection of the other side of said relay to earth switches TS_{31} and S_{38} causes the armature of relay S_{33} to move to the right breaking the circuit of relay S_{34} which de-energizing causes its armature to move to the lower contact for energizing switch LS_1 . Before this can take place, however, a momentary contact has been made from earth through the armature of S_{33} to relay S_{35} which momentarily shortcircuits the transmitting branch L_1 just before the switch LS_1 closes its inner contacts to the line through transformers T_1 , T_2 . When de-energized relay S_{32} also breaks the energizing circuit for relay S_{36} which prevents earth being put on the winding of relay S_{33} by manual operation of the switch TS_{31} so that after having established the circuit at the receiving end the speaker at the remote station maintains control of the circuit as long as he continues to speak.

On the inner contacts switch LS_1 being closed the telephone currents pass through the filter F_2 , amplifier A_{10} , equalizer E_2 , amplifier A_8 , amplifier A_6 to the line L_2 . Some of the current passes through the amplifier detector AD_{32} operating relay S_{30} which breaks the circuit of the amplifier detector AD_{31} so that the control of the relay S_{33} from line L_1 is broken. This holds the circuit for reception in L_2 independent of courier as long as the speech is continued. When speech in this direction ceases, however, relay S_{38} releases freeing relay S_{31} . On de-energizing relay S_{31} closes its contact. With the cessation of speech relay S_{30} de-energizes allowing its contact to close. Thus the circuit of S_{32} is re-established and on the receipt of speech in L_1 will again place earth on the winding of relay S_{33} to bring its armature to the left as above explained. Relay S_{37}

closes courier current C to the line over TS_{31} and filter F_4 .

In Fig. 3A a repeater similar in function to that of Fig. 1B is shown adapted to repeat in a system employing the courier current control. The same reference letters in Figs. 1B and 3A indicate like parts and their functions will not be again explained. Assuming telephone transmission be taking place from CW to CE, the switches would be in the position shown. They pass through filter F_6 to the outer contacts of switch LS_2 over the branch comprising filter F_7 etc. to the delay network D_3 , amplifier A_{12} , filter F_8 to the outer contacts of switch LS_3 and thence through transformers T_5 and T_6 and filter F_{10} to the cable CE. All the filters F_6 , F_7 , F_8 , F_9 , F_{10} are adapted to transmit telephone frequencies and suppress telegraph frequencies.

Suppose that speech in the said direction from CW to CE ceases and telephone current is received at CE from the opposite direction, then this speech would be preceded by a courier current which would traverse filter F_{11} , switch TS_{33} over amplifier TA , equalizer TE , phase compensator PC , zero wander corrector ZW , courier receiver REG , to relay S_{39} which on being operated places earth on the relays LS_2 and LS_3 closing the inner contacts thereof. This would connect the cable CE through filter F_9 , amplifier A_6 through D_3 , A_{12} , F_8 inner contacts of LS_2 to the cable CW over the transformers T_3 , T_4 .

The telegraph switches TS_{32} and TS_{33} for controlling the telegraph transmission are for simplification shown as manually operated simplex, and the co-operation between attendants to control the direction of transmission is on the well known simplex basis.

When switches TS_{32} and TS_{33} are positioned for telegraph transmission in the opposite direction i. e. from CW to CE, the switches LS_2 and LS_3 are normally operated and provide a telephone circuit from CE to CW. In such a case when relay S_{39} is operated by the receipt of courier the switches LS_2 and LS_3 are released changing the direction for telephone transmission.

In Fig. 3A we have shown how the principle of Fig. 1B may be modified for a system with courier current control and in similar manner the system as illustrated in Fig. 1C may also be adapted with suitable modification for a system with courier controlled switching.

Figures 4 and 4-A show the terminal stations of a submarine cable telephone and telegraph system in which the transmission features are similar to those previously described for other systems. In this system the direction of telegraph transmission is dependent on the direction of telephone transmission and is always in the same direction. The system is normally in a condition for

through transmission of both telephone and telegraph currents from the station shown on Figure 4—A to that shown on Figure 4.

Considering the operation of the station shown on Figure 4; speech received for transmission to the submarine cable along the line L_1 causes the amplifier detector AD_1 to operate the relay S_1 which short circuits the receiving apparatus, and the amplifier detector AD_2 connected between the submarine cable and the line L_2 . The relay S_1 causes operation of the line switch LS_1 for changing the connection of the submarine cable from the receiving apparatus to the transmitting amplifier associated with the line L_1 . This relay also causes the operation of the switch TLS_1 which performs a similar function for the telegraph circuit. The operation of the switch S_1 causes the operation of the switches S_2 and S_3 which are so timed that the switch S_2 operates before S_3 , thus sending a pulse of control current from the source of the control current C_2 through filter F_1 to the submarine cable. The cessation of speech on the line L_1 allows the switch S_1 to release the switches S_2 and S_3 and these are so arranged that the switch S_3 releases before the switch S_2 thus sending another pulse of control current to the cable. There is thus a pulse of control current before speech, which is delayed by the delay network, and a second pulse after the cessation of speech.

In the normal condition of the switch LS_1 received telephone current enters the apparatus connected to the receiving line L_2 and by means of the amplifier detector AD_2 causes operation of the switch S_1 , which short circuits both the input to the amplifier detector AD_1 and part of the apparatus connected to the line L_1 , thus preventing interference from noises and speech on the line L_1 .

The switch TLS_1 may have an extra contact which can be arranged to start the telegraph transmitter when the switch TLS_1 is in a position for the transmission of telegraph signals through the filter F_3 to the cable. The filters F_1 , F_2 and F_3 are designed to discriminate between the various currents required by the parts of the system connected to them. All the amplifiers in this figure are designated "A".

In Figure 4—A the line L_3 is connected through the transmitting amplifiers A_1 to the contacts of the switch LS_2 to the submarine cable. Extra contacts from this switch are arranged to short circuit the output of the intermediate stage of the receiving amplifier A_2 . The telegraph transmitter is also normally connected through the filter F_6 to the submarine cable. In this condition outgoing speech from the line L_3 can enter the submarine cable and performs no switching function.

The pulses of control current generated by the station shown in Figure 4 are received

through the filter F_4 and by means of the pulse receiver PR cause operation of the relay S_5 . The pulse preceding speech causes operation of the relay S_5 which connects earth over the normally made contacts of the relays S_8 and S_7 to cause operation of the relay S_6 . The operation of this relay causes the operation of the line switch LS_2 and the telegraph line switch TLS_2 which connects both the telephone and the telegraph receiving circuits to the submarine cable and prepares them for the reception of speech and telegraph respectively. After the cessation of this first pulse the relay S_6 remains operated through its contact and the winding of relay S_7 and the normally made contact of relay S_8 . The removal of the earth from the winding and contact of the relay S_6 allows the relay S_7 to operate. The operation of the relay S_7 connects the lead from the relay S_5 through the winding of the relay S_8 and battery. The reception of the pulse following speech causes operation of the relay S_8 . The operation of the relay S_8 disconnects the earth from the windings of relays S_6 and S_7 which then release causing the relays LS_2 and TLS_2 to release, thus restoring both telephone and telegraph circuits to the transmitting condition. When the relay S_5 releases after the pulse, relay S_8 releases and the train consisting of the relays S_6 , S_7 and S_8 are again ready for the reception of the pulses preceding and following the next period of speech.

The extra contact on the switch LS_2 is arranged to break the short circuit on the receiving amplifier after this amplifier has been connected to the cable. Any click generated at the moment of connection is thus suppressed. Similar clicks suppressing contacts can be included in the switch LS_1 shown on Fig. 4.

In the case of simultaneous telephony and telegraphy a convenient division of the frequency range would be 0 to 300 cycles for telegraph and 400 to 2,400 cycles for telephony, the space 300 to 400 cycles being unused to allow for the slope of the separating filters. In the case of dependent telegraphy this space can be made less than in the case of independent telegraphy because the attenuation necessary in the filters is smaller. The method in which the telegraph frequency range is occupied by telegraphy may differ in different cases but the use of a multiplex system occupying the range 0 to 100 cycles is contemplated while the range 100 to 300 cycles could be occupied by a similar multiplex system operated on carrier frequency of 200 cycles. An alternative method is to use a high speed distributor which may be of the thermionic valve type, transmitting at 600 bands. An alternative method where independent telegraphy is possible and which is probably preferable since it gives the effect of duplex working,

is to use the range 0-150 cycles for telegraph working in one direction and 150-300 cycles for telegraph working in the opposite direction. It will be understood that all figures quoted are merely given as examples and that circumstances might cause them to be considerably modified in value. In the case where full telegraph working is used over the system (i. e. without telephony) the whole frequency range which may be of the order of 0 to 2,400 cycles may be occupied by a number of voice frequency telegraph channels obtained by the modulation of a number of separate voice frequencies by different transmitting devices. Each transmitting device may be an ordinary telegraph transmitter or a number of ordinary transmitters operating through synchronized multiplex distributors. These distributors may be of the ordinary mechanical rotary type, or may be of the thermionic valve type. Transmission of the signals impressed on any carrier by modulation may be secured by sending both resultant sidebands and the carrier, by sending one sideband and the carrier or by sending one sideband alone. The last mentioned method is evidently preferable because it enables a larger number of channels to be obtained in a given frequency range. Synchronization of the telegraph signals can conveniently be carried out by a frequency located either in the speech range or in the telegraph range or outside or between the two; or alternatively synchronization by means of the signals themselves may be employed. In the case where a synchronizing frequency is employed within the range of speech for telephony, suitable means will be provided to balance it out at the receiving end. In the case where dependent telegraphy is employed and where the direction of telephony is changed from instant to instant with the direction of speech, known means will be employed by which controlled synchronizing oscillators at each terminal alternatively hold in step, and are held in step by each other as the direction of transmission changes.

In some cases it may be desirable to change the location of the speech range in the frequency spectrum by any suitable known process of modulation. For instance a speech range which may extend from 400 to 2,400 cycles per second could be moved to the range 0 to 2,000 cycles per second before transmission over the cable and could be reconverted at the receiving end.

What is claimed is:

1. In a submarine cable telephone system the combination with the cable of a circuit comprising a receiving branch and a transmitting branch, a switching device in said circuit adapted to connect said cable respectively with either the receiving branch or the transmitting branch and means for operating

said switching device by voice currents in said circuit.

2. In a submarine cable telephone system the combination with the cable of a circuit comprising a receiving branch and a transmitting branch, a voice current detecting device in each said branch, an amplifying device in each said branch, a switching device in said circuit adapted to connect said cable respectively with either the receiving branch or the transmitting branch under the control of voice currents in said circuit according to the direction of transmission and means under control of said voice current detecting device in one branch to disable the amplifying device in the other branch and vice versa.

3. In a submarine cable telephone system the combination with the cable of a circuit comprising a receiving branch and a transmitting branch, a switching device in said circuit normally positioned to connect one branch to said cable and means associated with the other branch and operative by voice currents therein to operate said switching device to connect said other branch to said cable.

4. In a submarine cable telephone system the combination with the cable of a circuit comprising a receiving branch and a transmitting branch, a switching device in said circuit normally positioned to connect the receiving branch to said cable, means associated with the transmitting branch and operative by voice currents therein to operate said switching device to connect said transmitting branch to said cable and means in said transmitting branch to delay the transmission of voice currents to the cable.

5. In a submarine cable telephone system the combination with the cable of a circuit comprising a receiving branch and a transmitting branch, voice current amplifying means in each said branch, a switching device in said circuit normally positioned to connect the receiving branch to said cable, means associated with said receiving branch and adapted to be operated by voice currents therein to disable the amplifying means in said transmitting branch, and means associated with the transmitting branch and adapted to be operated by voice currents therein to operate said switching device to connect said transmitting branch to said cable and to disable the amplifying means in said receiving branch.

6. In a submarine cable telephone system the combination with the cable of a filter adapted to pass telephone frequencies, a filter adapted to pass telegraph frequencies, a telephone circuit comprising a receiving branch and a transmitting branch associated with said first mentioned filter, a telegraph circuit comprising a receiving branch and a transmitting branch associated with said second mentioned filter, switching means adapt-

ed to connect said cable respectively either with said receiving branches or said transmitting branches and means operated by voice frequency currents for controlling said switching means.

7. In a submarine cable telephone system comprising terminating equipment at each end of the cable including transmitting and receiving branches and switching devices for connecting the cable alternately to said branches, the combination with the switching device at one end of the cable of means responsive to control currents transmitted over the cable and adapted to cause the operation of said switching device, and means at the other end of said cable responsive to voice currents for controlling the transmission of said control currents.

In witness whereof, we hereunto subscribe our names this 26th day of January, 1931.

EDWARD K. SANDEMAN.
